CLAIM

The ornamental design for a leash hanger, as shown and described.

DESCRIPTION

FIG. 1 is a front elevational view of a leash hanger showing my new design;
FIG. 2 is a bottom plan view thereof;
FIG. 3 is a rear elevational view thereof;
FIG. 4 is a right side elevational view thereof, the left
side being a mirror image of that shown; and
FIG. 5 is a top plan view thereof.
